CHESTER H. MILLS, OF WICHITA, KANSAS

SELF COMPUTING LEVELING ROD

Application filed April 2, 1928. Serial No. 266,507.

The invention relates to improvements in leveling rods used by surveyors and others, in which sliding elements are used to bring to view correct numerals as indicated by the line of sight of the levelman's instrument. Among the principal objects of the invention are; first, to provide a means of obtaining elevations by simply reading the figures intercepting the said line of sight; second, by means of specially devised locking elements, to prevent the movable parts of the rod from slipping while in use; third, to permit the use of a long rod, an intermediate rod, or a short self-computing rod as may be desired. By means of my invention a great saving of time is effected; also it greatly simplifies the matter of computations. My improved rod is much more easily handled than the computing rod generally employed and accuracy readings is assured. These and other advantages will be apparent from the description of the drawings and as specifically pointed out in the claims.

In the drawings; Fig. 1 represents a front view of my improved self-computing leveling rod, with parts broken away to enable the rod to be brought within the confines of the sheet. Fig. 2 is a rear view of Fig. 1. Fig. 3 is a side view of Fig. 1. Fig. 4 represents an enlarged side view of the base element seen in Fig. 2 with parts removed to disclose operative details. Fig. 5 is a side view of Fig. 4 omitting the screw element for convenience of illustration but showing base 13 not on Fig. 4. Fig. 6 represents a detail showing the upper rod release seen in Fig. 2 while Fig. 7 shows a side view of the same with parts removed from the view seen in Fig. 3. Fig. 8 represents a sectional view taken along the line VIII-VIII in Fig. 2 looking in the direction of the arrows; Fig. 8b represents a sectional view taken along the line b-b in Fig. 2 looking in the direction of the arrows; while, 8c represents a sectional view taken along the line c-c in Fig. 2 looking in the direction of the arrows. Fig. 9 is a detailed side view of the means for adjusting the front foot numeral plate as seen in Figs. 1, 2 and 3. Fig. 10 is a front view of Fig. 9

and showing the hook assembly on the bottom of the foot numeral plate of the upper rod. Fig. 11 represents a fragmentary portion of a foot numeral plate and its covering strip with openings therein through which desired numerals may appear in selected order. Fig. 12 shows front and side views of the automatic catch for the target. Fig. 13 shows front and side views of the automatic plate catch seen in Figs. 2 and 8b. Similar numerals of reference indicate corresponding parts throughout all the figures of the drawings.

Referring to the drawings; 10 represents the lower rod element while 11 represents the upper rod portion. Below the lower rod at 13 is seen the base member slidably positioned intermediate the paired U-shaped guides 14 and 15 attached to the rod 10. At 16 in Figs. 2 and 4 is a plate provided with a threaded boss 17 receiving the screw 18 rotated by the thumb nut 19 housed in bearings in the U-shaped bracket 20 which is attached by screws 21, 21 to the rod 10. Also the plate 16 is slotted near its ends as at 22 and 23 to pass screws 24 and 25 entered into the rod 10 as seen in Fig. 4, the slots 22 and 23 permitting the plate 16 to have vertical movements under adjusting conditions as required and carried out by the manipulation of the thumb nut 19 to move the boss 17. It will be noted in Fig. 5 that at spaced positions upon the face of the plate 16 are square cut grooves such as 26 adapted to receive the foot 27 of the plunger 28. A U-shaped plate 29 in Fig. 2 is attached by screws 30 (Fig. 2) to the base member 13 and is slotted at 31 to pass the head 28 of the plunger. At 32 Fig. 5 is a spring on the stem of the plunger 28 bearing between the enlarged portion 33' and the plate 29 normally forcing the foot 27 to engage a selected groove 26 which would lock the base element 13 in a fixed position relative to the rod 10. To break this locked connection the plunger 28 is drawn outwardly then given a quarter turn as in Fig. 2 or so that the head 28 stands transverse to the slot 31 and bears against the plate 29. This holds the foot 27 out of engagement

with a groove 26 to permit adjustments as later disclosed.

One of the main objects of the invention is to permit the locking of the upper rod at various foot elevations or so as to permit the rodman to employ a rod no longer than is necessary, and to provide a means for changing foot numerals.

At spaced intervals of a foot each upon the rear face of the rod 10 as seen in Fig. 2 are attached by screws, metallic sockets such as 33. Upon the base of the rod 11 is a base plate 34 (see Figs. 6 and 7) slotted at 35 to pass the disc 36, which is slidably mounted adjacent the head 37 of the plunger 38. In Fig. 6 the disc 36 has been slid upwardly to engage against the shoulder 35y to permit engagement of plunger 42 with socket 33 in Fig. 7 for locked position of extended rod. The plunger 38 is horizontally operative in an opening through the base of the member 11 and in which a lever 39 pivoted upon a fixed pin 40 and hinged at 41 to the plunger 38 actuates the plunger 42 against the spring pressure 43 to disengage said plunger 42 from the socket 33, or to permit the reverse movement as explained above. Pushing in and down upon the disc 36 breaks the plunger lock as in Fig. 7, the disc 35 locking behind the plate 34 as shown by dotted position 35x. Thus it will be seen that the upper rod can be quickly raised or lowered as may be desired so that no longer rod is used than is essential. This is of material advantage in leveling through trees and other close quarters.

At 44 is the usual target. At its topmost position it is positively positioned by means of the automatic catch seen in Figs. 3 and 40 12. A spring-actuated plunger 45 detachably engages the socket 46 for such purpose.

Upon the face of the rod 10 Fig. 1 is a foot numeral plate or strip 47 seen in Fig. 11. This strip may be shifted up or down upon the face of the rod 10 a short distance. The strip 47 is covered by a metallic strip or plate 48 which is graduated with spaced numerals 1 to 9 inclusive or as otherwise determined. The plate 48 is affixed to the rod 50 and is perforated to provide a square slot through which numerals on the shift strip 47 designating foot marks may appear, they being shown upon the strip 47 as in Figs. 1 and 11. These numerals are so spaced as will be observed so that if for instance the numeral seven appears in the slot 50 as in Fig. 11, then the numeral eight will appear in the next lower slot 50, numeral nine in the slot 50 below that etc., while numeral six would appear as in Fig. 1 in the slot above the numeral seven seen in its slot in Fig. 11. The strip 47 is shifted in either direction less than a foot or the distance necessary to expose ten numerals of a convenient size

to be seen through a slot 50 in the plate 48 as later explained. The purpose of this arrangement is such that if the end 49 of the base member 13 be rested upon a bench mark, its known elevation is adjustably transposed upon the rod or so that once this has been established all further elevations may be read direct from the rod without further calculations. Assuming for instance an elevation of the bench mark of 106.1. The strip 47 would be shifted by means later described until numeral 6 appears in the opening or slot 50 in the plate 48 closest to the line of sight. This would not necessarily bring the proper decimal in this case .1 exactly into the line of sight. The member 28 would be pulled out to break connection of the element 27 with the groove 26 it might be in, then the plate 16 would be again engaged by such element 27 within a more proper groove 26 closest to the line of sight, thence by adjusting the screw 18 the plate 16 would be finally shifted in its guides 22 and 23 to the exact point so that the line of sight would read for instance the 6.1 portion of the bench mark reading 106.1 above mentioned for purposes of illustration. Readings appliance to the lower rod at any other points at which elevations were desired would be read direct from such rod, for wherever the line of sight would intersect such lower rod the proper foot numeral be it 6, 7, 8 and 9 would show through its proper slot 50 and the remainder of the elevation would be read from the strip 48. It will thus be seen that the slots 50 are maintained in a fixed position upon the rod 10 and the strip 47 merely slides up or down a foot or less distance behind the plate 48 so that the proper numerals register in series through said slots 50 for the purposes designated. The shifting of the plate 47 above referred to is accomplished by the means illustrated in Figs. 3, 9 and 10. A slot 51 as in Fig. 8 is made through the side of the upper end of the rod 10. A plate 52 of L-shape slidably arranged therein is screwed to a second L-shaped plate 53 (Fig. 8) which in turn is riveted to the plate 47. At 54 (Fig. 3) is a slotted strip having ten transverse slots such as 55 intersecting the long slot 56 of the strip 54. A slideable element 57 having a handle element 58 has a pair of slots receiving the pins 59 on the plate 52 or so that the handle 58 may be pulled out to disengage its base from any cross slot 55 and permit the handle to move vertically into a new position to register with any other selected slot 55 thus moving the strip 47 to bring the proper numeral such as the six above referred to, near the line of sight and to set the other numerals in their proper windows for rod reading purposes. The spring 60 (Fig. 9) engages a 130

notch in the plate 52 to hold the part 57 against movement.

A plate similar to 47 appears upon both faces of the upper rod 11 and each face has 5 a covering plate similar to the plate 48. The plates 47x and 47y Figs. 2 and 8c are connected through a slot in the upper end of rod 11 by a cross tie 61 riveted to each. The composite plates 47x—47y are adjusted by 10 means of a projection 62 on plate 47x which is slidably arranged in the guide 63. The slots in which the members 52, 53 and 61 slide are of the correct length to allow all foot numerals 0 to 9 to be shown in their 15 desired openings in the plates 48, 48x and 48y. These plates are rigidly attached by screws flush with the surface of the rods 10 and 11.

Pushing up or down upon the member 62 20 moves the plates 47x—47y to any desired locked position as illustrated in Figs. 8b and 13. This causes foot numerals on the plates 47x and 47y to appear in the proper slot 50 of the upper rod 11. Holes such as 64 are 25 drilled in the plate 47x at spaced intervals, corresponding to the spacing of the slots 55, to receive the spring actuated plunger means 65 to hold the proper foot numerals in their respective slots 50 as above. The plunger 30 65 automatically locks or detaches as will be readily understood.

Fig. 10, which is a detail of the dotted portion at 53, Fig. 3 also includes at the 35 upper left hand corner thereof a small plan view of the strip 47y and hook 66 riveted to the base thereof. The plate 47 on member 10 being held in its proper position by the plunger 58, the upper rod, if raised to its full length, causes the hook 66 to engage the 40 hook 67 on the member 53; the plunger 65 releases and the rod 11 extends to its full length, the hook engagement 66—67 holding then the plates 47x and 47y in proper position to conform to the lower plate 47 or so 45 that the proper foot numerals on the extended rod 11 will then appear through their slots 50 and check with the foot numerals upon the lower rod 10 and in proper spaced order. This then gives the correct reading 50 for the entire length of the rod 10—11. The hook 66 slides in the groove 68 in Fig. 2. The rod is raised to its full length, the member 34 striking against the metallic stop 69 in Figs. 1 and 2. When the rod is 55 fully closed it rests against the metal stop 70, Figs. 1, 2 and 3. If target is to be read, then the elevation is read by the rodman on the back of the upper rod 11.

My rod is more accurate than other rods 60 since the part 17, 19 and 20 give a fixed adjustment. Where rollers are used exact readings are impossible, owing to the fact that they are liable to wear, and ribbons or ribbon rods are liable to slip upon rollers 65 and are also subject to variation caused by

expansion and contraction of the ribbon. Exact readings are possible with my rod due to the fact that they are taken on the fixed wood part of the rod.

Such modifications may be employed as 70 lie within the scope of the appended claims.

Having fully described my invention, what I now claim as new and desire to secure by Letters Patent is;

1. In a device of the class described, a 75 lower rod and an upper rod slidably associated; an extension below the lower rod as a base element and means for adjustably positioning the same with respect to said lower rod; said means including a plate slidably mounted on the lower rod near the base thereof, said plate having openings for receiving a plunger mechanism; a plunger mechanism carried by the extension member and adapted to engage within a selected 80 opening in said plate for adjustably positioning the parts as previously stated.

2. In a device of the class described, a lower rod having a plate slidably mounted thereon near the base thereof, an extended 90 foot portion and a plunger mechanism associated therewith; said plate having openings for receiving said plunger mechanism, said plunger means being positioned within said extended portion at the base of the lower 95 rod and to enable varied positions of the rod and extended portion to be maintained as desired.

3. In a device of the class described, an upper rod having strips on opposite faces, 100 each having openings therein; a pair of sliding strips connected at their top ends through a slot in said rod, said strips being arranged to move behind the face strips with which they are allied, each strip bearing numerals in series readable through said openings in proper series relationship; and means for securing said strips in adjusted position at selected intervals; one of said strips carrying a hooked end; a lower rod 105 slidably connected to the upper rod, a face strip thereon, a sliding strip carrying foot numerals arranged behind the face strip with openings therein to permit viewing of proper foot numerals in series; means for adjustably setting said strips to expose said foot numerals at proper slotted openings and a hook assembly on said setting means for engaging the hook on the strip of the upper rod to 110 properly associate the lower numeral strip with the upper numeral strips under extended rod conditions to present a proper spacing of foot numerals at slotted places of the upper and lower rods for reading purposes. 115

4. In a device of the kind described, an upper rod having strips on opposite faces affixed to the rod, each strip having openings at spaced intervals; a pair of sliding strips connected at their top ends through a slot 120

in said rod, said strips being movable behind said face strip a short distance in either direction and numerals in series marked on said strips and readable through
5 said openings in a proper series relationship.

In testimony whereof I affix my signature.
